INVENTOR

UNITED STATES PATENT OFFICE

95,995

DESIGN FOR A SHOE

Abraham Turiansky, New York, N. Y.

Application May 11, 1935, Serial No. 56,787

Term of patent 3½ years

To all whom it may concern:

Be it known that I, Abraham Turiansky, a citizen of the United States of America, residing in Manhattan, county of New York, and State of New York, have invented a new, original, and ornamental Design for a Shoe, of which the following is a specification, reference being had to the accompanying drawing, forming part thereof, wherein,

The line extending from the end buckle at the instep of the shoe, and the lines extending down from the band portion of the shoe, represent a fold in the ribbon.

I claim:

The ornamental design for a shoe, substantially as shown and described.

ABRAHAM TURIANSKY.
